(57) **CLAIM**

We claim the ornamental design for retractable banner stand, as shown.

DESCRIPTION

FIG. 1 is a front perspective view of a retractable banner stand according to the invention with the banner extended.

FIG. 2 is a rear perspective view of a retractable banner stand according to the invention with the banner extended.

FIG. 3 is an end view of a retractable banner stand according to the invention with the banner extended. The view from the opposite side being a mirror image thereof.

FIG. 4 is a front perspective view of a retractable banner stand according to the invention with the banner retracted.

FIG. 5 is a rear perspective view of a retractable banner stand according to the invention with the banner retracted.

FIG. 6 is an end elevational view of a retractable banner stand according to the invention with the banner retracted. The view from the opposite side being a mirror image thereof; and,

FIG. 7 is a top plan view of a retractable banner stand according to the invention with the banner retracted.

The dashed lines illustrate features or environment that are not part of the claimed invention.
